George J. Webster, ATTORNEY

UNITED STATES PATENT OFFICE.

EDWARD W. THOMAS, OF STOCKTON, CALIFORNIA.

GREASE-CUP.

1,187,871.

Specification of Letters Patent. Patented June 20, 1916.

Application filed November 10, 1914. Serial No. 871,243.

To all whom it may concern:

Be it known that I, EDWARD W. THOMAS, a citizen of the United States, residing at Stockton, in the county of San Joaquin, 5 State of California, have invented certain new and useful Improvements in Grease-Cups; and I do declare the following to be a clear, full, and exact description of the same, such as will enable others skilled in the art to which it appertains to make and use the same, reference being had to the accompanying drawings, and to the characters of reference marked thereon, which form a part of this application.

15 This invention relates to improvements in grease cups and particularly to that type used on large bearings such as are found on locomotives and similar machinery, the object of the invention being to produce a 20 grease cup having a means for locking the cap in position against losing and at the same time providing a means for admitting of a predetermined amount of lubrication for any given number of revolutions of the 25 bearings to be lubricated.

A further object of the invention is to produce a simple and inexpensive device and yet one which will be exceedingly effective for the purposes for which it is de- 30 signed.

These objects, I accomplish by means of such structure and relative arrangement of the parts as will fully appear by a perusal of the following specification and claims.

35 On the drawings, similar characters of reference indicate corresponding parts in the several views.

Figure 1 is a top plan view of the preferred form of my invention. Fig. 2 is a 40 side elevation of the same partly broken out and in section. Fig. 3 is a top plan view of a modified form. Fig. 4 is a side elevation of the subject matter shown in Fig. 3. Fig. 5 is a side view in section of still another modification of the invention.

Referring now more particularly to the characters of reference on the drawings, the numeral 1 designates the grease cup proper, which is of the usual interior threaded type, 50 while the numeral 2 designates the cap of the same having the usual wrench socket 2^a or other suitable operating member.

My improved invention embodies two or more notches 3 cut into the outside edge of 55 the cap 2 and adapted to receive a spring pressed pin 4 mounted on the cup 1 and en-

gageable with one of said notches 3 to prevent rotation of the cap 2. In the preferred form of the invention this pin 4 is mounted on a spring wire 5 secured to the cup 1, the tension of which spring normally holds said pin in engagement with one of the notches 3. In order to remove the pin 4 from the notch 3 to allow the rotation of the cap 2, I have provided a small handle 6 pivotally mounted 60 on the lip 7 on the wire 5 and provided with a curved cam 8 engageable with the side of the cup 1 whereby, with the movement of the handle 6, the spring wire 5 will be moved away from the side of the cup 1 65 carrying with it the pin 4 and thus releasing the pin 4 from one of the notches 3.

The structure above described is susceptible of two functions, namely, the cap 2 will be locked against being shaken loose by the 75 vibration of the machinery and becoming lost and at the same time the notches 3 can be so spaced that with the movement of the cap 2, the distributor between one notch and the other will force any amount of grease 80 from the cup 1 sufficiently to lubricate the bearing for a given number of miles.

In the cap 2 of the grease cup, I have provided a central chamber 14, the lower and upper extremities thereof having inwardly 85 projecting shoulders 15 and 15^a, respectively, the shoulder 15^a forming sort of an auxiliary chamber 16 above the chamber 14. The object of this particular structure is to prevent too rapid an outflow of the grease. 90 When the cup becomes warm, due to the heat received from adjacent moving parts, the grease becomes warm and hence softens and has a tendency to run too freely from the cup. This tendency is retarded by the fact 95 that the inwardly projecting shoulders 15 and 15^a cause the grease in the intervening space 14 in a measure to be locked in position, and also prevents any air from easily reaching the chamber 16. By reason of this 100 latter condition, a sort of a vacuum is formed in the chamber 16 so that together with the locking shoulders 15—15^a and this vacuum, the tendency of the grease to flow out too rapidly is largely overcome.

In the structure shown in the modified form in Figs. 3 and 4, the numeral 1^a designates the cup, 2^a the cap and 3^a the notches. Instead of the pin 4 I provide a spring 105 pressed ratchet 4^a pivotally mounted between lips 7^a on the side of the cup 1^a, which ratchet projects into one of the notches 3^a.

This ratchet 4^a normally holds the cap 2^b against movement, but by releasing it from the notch 3^a, movement can be had, as described above.

5 In the modified form shown in Fig. 5, the numeral 1^b designates the cup, 2^c designates the cap and 3^b the notches. The pin 4^b is provided with a collar 9 moving in a small cylinder 10 secured to the side of the cup 1^b 10 with a spring 11 interposed between the end of the cylinder and the collar 9 to hold the pin 4^b normally in engagement with one of the notches 3^b. A handle 12 is hinged to the pin 4^b and projects outside of the cylinder 15 10. To remove the pin 4^b from the notch 3^b, the handle 12 is operated to pull the collar 9 against the spring 11 until the hinged point 13, between the handle 12 and the pin 4^b, is outside of the cylinder 10 when the handle 12 may be moved on its hinged point 10 and locked against the end of the cylinder 10 to hold the pin 4^b out of engagement with the notch 3^b as long as may be desired.

From the foregoing description it will 25 readily be seen that I have produced such a device as substantially fulfills the objects of the invention as set forth herein.

While this specification sets forth in detail the present and preferred construction 30 of the device, still in practice, such deviations from such detail may be resorted to as do not form a departure from the spirit of

the invention as defined by the appended claims.

Having thus described my invention what 35 I claim as new and useful and desire to secure by Letters Patent is:—

1. A device of the character described comprising in combination a grease cup, a cap threaded into said cup, the said cap being provided with an interior chamber having its upper portion reduced in diameter, an inwardly projecting flange at the lower end of such chamber, and means for locking said cup against rotation as described. 40 45

2. A device of the character described comprising the combination with a grease cup, of a cap threaded into said grease cup and provided with notches in its side, a spring pressed member mounted on said cup 50 and engageable with said notches, a cam pivotally mounted on said spring pressed member and arranged to be brought into engagement with the side of said cup to remove such spring pressed member from engagement with said notches, and a handle mounted on said cam, as described. 55

In testimony whereof I affix my signature in presence of two witnesses.

EDWARD W. THOMAS.
